SIREN ROTOR

Filed Aug. 9, 1930

FIG. 2

FIG. 3

FIG. 4

FIG. 5

INVENTOR.
LESTER H. MILES.

BY

ATTORNEY.

UNITED STATES PATENT OFFICE

LESTER H. MILES, OF LOS ANGELES, CALIFORNIA

SIREN ROTOR

Original application filed August 20, 1929, Serial No. 387,247. Divided and this application filed August 9, 1930. Serial No. 474,157.

This invention relates to a siren.

The general object of this invention is to provide an alarm or signal device in which an improved rotor having a forwardly open pocket is employed.

Other objects of the invention will be apparent from the following description taken in connection with the accompanying drawings wherein:

10 Fig. 1 is a central longitudinal section of my improved siren.

Fig. 2 is a section on line 2—2 of Fig. 1.

Fig. 3 is a section of the rotor on line 3—3 of Fig. 2.

15 Fig. 4 is a view similar to Fig. 2 showing a modification and

Fig. 5 is a section of the rotor on line 5—5 of Fig. 4.

This application is a division of and addition to my co-pending application Serial No. 387,247, filed Aug. 20, 1929.

Referring to the drawings by reference characters I have indicated my invention as embodied in a siren indicated generally at 25 10. As shown in the drawings the siren 10 comprises a casing indicated generally at 11. This casing includes a hollow cylindrical body portion 12 and a cover plate 13 having a reduced hollow cylindrical hub or port 20 member 14 thereon. The body 12 is also provided on its outer periphery with a plurality of spaced apertures or ports 15 as clearly shown in Figs. 1 and 2, and a hollow boss 16, the function of which will be later described.

35 Mounted within the body 12 is a rotor 17. This rotor comprises a flat circular rear plate 18 provided at its center with a curved hub 19 and on its outer periphery with a plurality of short, arcuate spaced flange segments 20.

40 Connecting the front edges of the flange segments 20 I provide a circular disk 18^a which is approximately the same diameter as the back plate 18 and is provided with a central aperture 18^b. From the trailing end of each flange 20 a vane 21 extends inwardly. Each vane preferably comprises a short curved portion 22 and a longer curved portion 23 with the end of the portion 23 spaced from the base of the curved hub 19. The vanes 22 45 are preferably of uniform height throughout

and they are curved outwardly so that the portion 21 is ahead when the rotor is rotated.

The construction is such that when the rotor 17 is revolved the vanes 21 force the air outwardly from the center through the apertures at the end of the flanges 20 and through the ports 15 of the casing. As the air is forced outwardly and the ports 16 are intermittently opened and closed by the rotor flanges 20 a loud noise is produced. The absence of connection between the vanes and the hub 19 and the shape and arrangement of the vanes, all combine to lessen the resistance as the rotor revolves while increasing the volume of sound produced.

55 The spacing of the ends of the vanes from the hub 19 also allows more air to enter the chamber between the vanes and thus a greater quantity of air may be forced out through the ports 15, thereby producing a much louder noise than if all the vanes ran direct to and were connected with the hub 19. Further, the pockets 25 formed at the juncture of the segments 20 and the vanes 21 trap air therein and produce an air compression function which augments the sound produced.

65 The rotor 17 is shown as mounted on a shaft 25. This shaft is provided with suitable bearings 26 and 27 fitted within the boss 16 of the casing. The shaft 25 has an enlarged flange 28 thereon which engages the bearing 27. The shaft 25 and the rotor may be secured together as by a nut 29.

70 The rotor 17 is shown in the drawings as adapted to be driven by a disk 30 which may be adjustably mounted on the shaft 25 as shown. The rotor may, however, be driven in any other desired manner.

75 In Figs. 4 and 5 I show a siren wherein the casing 12' is similar to the casing 12. In this modification the rotor 30 has peripheral flange segments 31 thereon and a hub 32. A vane 33 is attached to each segment 31 between the body thereof. Each vane comprises a straight portion 34 and a curved portion 35 which terminates short of the hub 32. The edge 36 of each vane is the leading edge and the construction of the vanes with the pockets 80

37 therein produces a loud sound when the rotor is turned.

From the foregoing description it will be apparent that I have invented an improved 5 siren which is highly efficient and which can be economically manufactured.

Having thus described my invention, I claim:

1. In a siren including a casing having a 10 rotor mounted thereon, said rotor including a base plate having spaced flange sections thereon, a vane extending from a trailing portion of certain of said flange sections, each of said vanes comprising an inwardly extending portion and a forwardly projecting portion to 15 form a forwardly open pocket.

2. In a siren, a casing, a rotor in said casing, a plurality of flange portions on said rotor, a plurality of vanes associated with 20 said flanges, said vanes being connected to a trailing portion of said flange portions to form forwardly open pockets.

3. In a siren, a casing, a rotor mounted in said casing, said casing having peripheral 25 apertures therein, said rotor having spaced flange segments thereon, a vane extending from the rear portion of certain of said segments to provide forwardly opening pockets.

4. In a siren, a casing, a rotor in said casing, said rotor including a base plate having spaced flange sections thereon, a vane extending from a rear portion of said flange sections, said vanes comprising a short U-shaped portion and a longer curved portion 35 connected to said U-shaped portion.

5. In a siren, a casing, a rotor in said casing, said rotor having spaced flange sections and a vane extending from a location in the rear of the front end of certain of said flange 40 sections whereby a forwardly open pocket is formed.

6. In a siren, a casing, a rotor, said rotor including a plate having spaced flange sections thereon and a vane extending from the 45 rear end of certain of said flange sections, said vanes being arranged to form a forwardly open pocket in conjunction with said flange sections, the inner end of said vanes being arranged to lead when the rotor is 50 rotated.

In testimony whereof, I hereunto affix my signature.

LESTER H. MILES.
